ATTORNEY

UNITED STATES PATENT OFFICE.

SUMNER A. ELY, OF NEW YORK, N. Y.

DESIGN FOR A SAFE OR VAULT DOOR.

52,733.

Specification for Design.

Patented Dec. 10, 1918.

Application filed June 5, 1918. Serial No. 238,396. Term of patent 7 years.

To all whom it may concern:

Be it known that I, SUMNER A. ELY, a citizen of the United States, residing in the borough of Manhattan, city, county, and State of New York, have invented a new, original, and ornamental Design for Safe or Vault Doors, of which the following is a specification, reference being had to the accompanying drawing, forming part thereof. The figure is a front elevation of an

opened safe or vault door showing my new design.

I claim—

The ornamental design for a safe or vault door as shown.

SUMNER A. ELY.

Witnesses:

DYER SMITH,
I. MCINTOSH.
